US0D1074284S

(12) **United States Design Patent** (10) **Patent No.:** **US D1,074,284 S**
(45) **Date of Patent:** **** May 13, 2025**

(54) **BASE SUPPORT**

(71) Applicant: **Shenzhen Fancyteck Technology Co., Ltd.**, Shenzhen (CN)

(72) Inventor: **Junhao Hu**, Shenzhen (CN)

(73) Assignee: **Shenzhen Fancyteck Technology Co., Ltd.**, Shenzhen (CN)

(**) Term: **15 Years**

(21) Appl. No.: **29/835,861**

(22) Filed: **Apr. 22, 2022**

(51) LOC (15) Cl. **06-06**

(52) U.S. Cl.

USPC **D6/708.1**; D11/130

(58) **Field of Classification Search**

USPC D6/329, 334, 349, 351, 355, 358, 702, D6/708, 708.1, 708.17, 708.2; D8/374; D11/117, 118, 130, 131, 157, 164; D24/215; D30/160, 199

See application file for complete search history.
